UNITED STATES PATENT OFFICE.

ALBERT DUIS, OF STREATOR, ILLINOIS.

RESERVE CARBID-HOLDER FOR ACETYLENE-GAS GENERATORS.

1,108,979.

Specification of Letters Patent.

Patented Sept. 1, 1914.

Application filed March 21, 1914. Serial No. 826,285.

To all whom it may concern:

Be it known that I, ALBERT DUIS, a citizen of the United States, residing at Streator, in the county of LaSalle and State of Illinois, have invented a new and useful Reserve Carbid-Holder for Acetylene-Gas Generators, of which the following is a specification.

The present invention relates to improvements in reserve carbid holders for acetylene gas generators, the same having been disclosed previously in applicant's patent dated February 24, 1914, No. 1,088,064, one object of the present invention being the provision of a pivotally swung reserve carbid holder mounted within and carried by the main carbid holder in combination with means carried by the bell and in the path of the pivoted reserve carbid holder, whereby the bell may be oscillated to tilt and empty the reserve carbid holder.

A further object of the present invention is the provision of a reserve carbid holder comprising a receptacle connected to a rod, said rod being pivotally mounted in the main carbid holder in the path to receive the carbid when filling the main carbid holder so as to insure the filling of the reserve carbid holder, the outer end of the rod being projected beyond the main carbid holder and extended upwardly to receive means carried by the bell so that the bell when oscillated will tilt the reserve carbid holder and precipitate the carbid into the main carbid holder.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a vertical central sectional view of the upper portion of a complete acetylene gas generator with the present carbid holder in operable relation thereto. Fig. 2 is an enlarged detail illustrating the various positions of the reserve carbid holder and the bell.

Referring to the drawings, the generating casing 1 has mounted thereupon the gas washer 2 and superposed thereabove is the

main carbid holder 3 provided with the detachable plugged inlet 4 by means of which carbid is placed within the main carbid holder. A bell 5 is disposed to encompass or incase these members so that the same may be raised or lowered due to the increasing and decreasing volume of the gas. The bell 5 is provided with a handle 6 by means of which the same may be oscillated as will presently appear.

A rod 7 is journaled within the upper portion of the main carbid holder and is provided with an arm 8 which is disposed exteriorly thereof and projected above the upper surface, there being attached to the rod 7 within the main carbid holder two apertured lugs 9 which carry the reserve carbid holder or curved plate 10. This reserve carbid holder or curved plate 10 is disposed directly below the inlet 4, so that whenever the main carbid holder is filled or charged with carbid, the receptacle 10 will also be filled, thus insuring at all times the proper filling of the reserve carbid holder.

Attached by means of the valved cock 11, to the under side of the top of the bell 5 and for disposition above the arm 8 of the rod 7 is a plate 12, provided with the two downwardly depending and parallel lugs 13, which when the bell is in its lowermost position due to the decreased volume of gas, the upper end of the arm 8 will be disposed therebetween or as illustrated in Fig. 2, so that when the bell 5 is oscillated through the instrumentality of the handle 6, the arm 8 will be engaged by one of the flanges or lugs 13 and thus be caused to assume the dotted line position as shown in Fig. 2, this action tilting the receptacle 10 so that the carbid held therein in reserve is emptied or dumped into the main carbid holder.

The reserve carbid holder is of such a capacity as to furnish sufficient gas for a night's use, so that the apparatus need not be disturbed for recharging until daylight.

What is claimed is:

1. In an acetylene gas generator, the combination with a main carbid holder and a bell disposed thereabove for vertical and oscillatory movements, of a reserve carbid receptacle mounted within the main carbid holder, and coöperable means carried thereby and the bell, whereby when the bell is in its lowermost position and is oscillated, the reserve carbid receptacle is emptied.

2. In an acetylene gas generator, the com-

bination with a main carbid holder and a bell mounted to surround the same for oscillatory and vertical movements, of a reserve carbid holder, including a receptacle mounted in the upper portion of the main carbid holder for swinging movement, an arm carried thereby and projecting exteriorly of the main carbid holder, and a lug carried by and projecting from the under side of the bell for disposition in the path of said arm whereby when the bell is oscillated, the reserve carbid receptacle is tilted and emptied.

3. In an acetylene gas generator, the combination with a main carbid holder provided with a carbid inlet and a bell surrounding the same for oscillatory and vertical movements, of a reserve carbid holder, including a rod mounted for swinging movement within the main carbid holder and directly below the carbid inlet thereof, a reserve carbid receptacle suspended from said rod and movable therewith, an arm connected to the outer end of the rod and projecting exteriorly of and above the main carbid holder, and a plate attached to the under side of the dome of the bell and having two parallel flanges extending therefrom for disposition in the path of to engage the arm of the rod when the bell is in its lowermost position, whereby when the bell is oscillated the rod and receptacle are tilted to empty the reserve carbid.

4. In an acetylene gas generator, the combination with a main carbid holder provided with a carbid inlet and a bell surrounding the same for oscillatory and vertical movements, of a reserve carbid holder, including a rod mounted for swinging movement within the main carbid holder and directly below the carbid inlet thereof, a reserve carbid receptacle suspended from said rod and movable therewith, an arm connected to the outer end of the rod and projecting exteriorly of and above the main carbid holder, and a plate attached to the under side of the dome of the bell and having two parallel flanges extending therefrom for disposition in the path of to engage the arm of the rod when the bell is in its lowermost position, whereby when the bell is oscillated the rod and receptacle are tilted to empty the reserve carbid.

5. In an acetylene gas generator, the combination with a main carbid holder provided with a carbid inlet and a bell surrounding the same for oscillatory and vertical movements, of a reserve carbid holder, including a rod mounted for swinging movement within the main carbid holder and directly below the carbid inlet thereof, a reserve carbid receptacle suspended from said rod and movable therewith, an arm connected to the outer end of the rod and projecting exteriorly of and above the main carbid holder, and a plate attached to the under side of the dome of the bell and having two parallel flanges extending therefrom for disposition in the path of to engage the arm of the rod when the bell is in its lowermost position, whereby when the bell is oscillated the rod and receptacle are tilted to empty the reserve carbid.

6. In testimony that I claim the foregoing as my own, I have hereto affixed my signature in the presence of two witnesses.

ALBERT DUIS.
